CHANGEABLE ADVERTISING DISPLAY

Edward S. Corcoran, Baltimore, Md.

Application June 9, 1938, Serial No. 212,797

3 Claims. (Cl. 40—76)

This invention refers to advertising signboards and more particularly to one that is moveable and changing and capable of being used with a trailer attached to a motor vehicle. It has among its objects, to provide a signboard of this nature that will have four possible signs, or sets of signs on each surface or wall; that will work intermittently so as to present the signs consecutively to view, that will be simple but effective in construction; that will be capable of special effects that attract attention, which will have all the signs on the signboards in operation at the same time on all sides or walls of the housing that holds them all erected on the trailer.

15 Signs on vehicles are usually of two types. One type being permanently affixed and disclosing the ownership of the vehicle; and the other being semi-permanent in that it can be affixed or removed at will. In the last case, the sign is usually of cloth or some light material that can be thrown over the body of a vehicle, fastened with buttons or the like, and then removed at will when the vehicle is to be used for other purposes. This invention is not strictly in either 20 class, but in one of its own, as it provides a system of sign-boards for trailers that are permanent structurally but changeable interiorly and intermittently to present different sets of same, as the trailer travels along. To get this result, the 25 invention has a series of slats that are preferably of translucent material, and arranged to rotate in quarter turns to present new signs at every such turn.

Normally, there are signs made up for each of 30 the two sides of the slats with another set arranged in back likewise, on secondary slats, that can be seen when the slats are horizontal, and thus provide another picture when the front slats are in that position. The slats are made 35 narrow to make them more effective, and to bring the rear set close to the front ones and thus present their designs to be clearly seen by the spectator in the street. The vehicle preferably 40 operates the mechanism that propels the slats, as it moves along the street, with provision to 45 operate the same manually if desired.

In the drawings which illustrate an embodiment of this invention:—

Figure 1 is a view in perspective of a trailer 50 vehicle carrying signs and housing embodying this invention,

Figure 2 is a section through a portion of the housing to indicate the construction and mechanism for operating the slats, taken along line 55 2—2 of Figure 3,

Figure 3 is a section through the portion of the housing showing the roof sign operating mechanism,

Figure 4 is a sectional elevation along line 4—4 of Figure 2.

Similar reference characters refer to similar parts throughout the drawings.

In the construction shown in the drawings 1 represents a platform on a trailer chassis 2 of conventional design. A housing 3 is mounted on 10 the platform and contains a series of sign boards 5 on five walls of the housing. Lights 4 on the platform provide illumination from the exterior for the signs, when required.

The front signs or signboards 5 are framed in 15 the housing as indicated by the portions 6 of the housing and may or may not have glass windows 7 to protect the signs themselves. The signs are made up of a plurality of narrow thin slats 8 supported on central shafts 9 that project into bearings 10 on the housing interior. The end portions 15 of the shaft are of square cross-section to assist in the turning of the slats. The slats fit closely to each other, and are painted with the desired slogan or sign wording on both sides. 20 The slats are preferably of translucent material to permit special lighting effects from the interior. 25

A suitable chain mechanism 21, with claws 12 and running over sprockets 13, supported in bearings 14 on the housing, provide arrangements for 30 rotating each of the slats intermittently. As the claws engage and move against the squared end portions 15, they pull on them and rotate them through a quarter turn, a spring 16, serving to 35 prevent further movement for the time being. The spring is suitably attached to the housing construction, is stationary, and is of the flat type. Then when the next claw is brought into 40 engagement, the squared end portion with each front slat is rotated another quarter turn. The motion of the vehicle transmits power from the axle 17 through a transmission 19, to a common series of shafts 18, that in turn transmit the motion to the upper shafts 20 through chains 21 45 and in turn operate the claws 12 that turn the central shafts 9 of the slats. The shafts 18 with their bevel gears 23 serve to tie all the front signs into a uniformly operating system. A manual device 24 permits the mechanism to be operated 50 by hand if desired, independent of the axle operation.

Another series of sign slats 28 are constructed and mounted similarly in the rear of the first mentioned slats and in the same manner and rotated intermittently, through the 55

chains 21 and claws 12. The shafts for the roof sign operate similarly to the wall slats and receive power or motion from the transmission chain 22 connecting the roof and wall sign slats together. In back of the slat signs are placed stationary signs 11 that may or may not be utilized, as a background sign in addition to the others, if desired.

In operation, the trailer travels along the roadway and its axle 17 turns. The turning of the axle through the transmission mechanism turns the chains 19, 21 and 22, and brings the claws into engagement with the squared end portions of the central shafts of all the slats and rotates them through a quarter turn. This brings the front slats from a vertical position to a horizontal and shows the picture on the slats in back, which are arranged to be vertical at the time. The slats in front are then rotated another quarter turn to bring the slats vertical, with their pictures facing the observers. The next quarter-turn movement causes the front slats to assume an open-slat position. This position allows the slats in the rear to be seen, with whatever illustrations may be on them, since these last mentioned slats are in the vertical position. The vertical position always presents the slats with the flat sides facing the eye of the observer standing in front of same. In other words, when the front slats are horizontal or in open position, the rear slats are vertical or in closed position, and vice-versa. The next quarter turn of the front slats brings them into vertical position with the flat sides facing the public. This last position brings the flat faces of the front slats to view, which flat faces are on the opposite sides of the slats to those that were shown by the front slats previously. The following table gives the movements of the slats during the consecutive quarter turns:

40 *Movements of sign slats*

Quarter turn	Front slats	Rear slats	Picture seen on—
45 1st.....	Vertical.....	Horizontal.....	Face of front slats.
2nd.....	Horizontal.....	Vertical.....	Face of rear slats.
3rd.....	Vertical.....	Horizontal.....	Back of front slats.
4th.....	Horizontal.....	Vertical.....	Back of rear slats.
1st.....	Vertical.....	Horizontal.....	Face of front slats.

50 Repeating in consecutive order as before.

It is, of course, understood that the rear pictures are seen on the vertically arranged rear slats, through the front slats when the latter are horizontal, because of the slight visual obstruction that the thin edges of the slats offer when the front slats are in such position.

By using translucent material for the slats, lights can be used in back of them to provide illumination for special effects, such as of colored circles 34, or the like, with lights 35 mounted within the interior of the housing.

First, the illumination is from the front, and then the secondary illumination is thrown on to bring out the colored circles, squares or other 60 regular figures that may be painted on the slats.

The position of the circles can be so that the secondary illumination will show through, no matter which vertical position the slats are in. Thus if the front slats are vertical, the colored devices will appear to the eye of the observer, 5 if they are on the front slats because they are shown directly to him through the use of the rear lighting. The secondary illumination will shine through and between the horizontal slats to the front slats and illuminate same, in this 10 case. If the rear slats are vertical, the illumination will enlighten them and make them appear to the observer. In other words, the same secondary lighting will illuminate either front or rear slats, when the slats are of translucent material, and the lighting is placed in back of the 15 rear slats. The device is effective because the slats showing one sign, suddenly change to a depth sign in back; and then back to another sign on the front slats, which is different to that 20 which appeared before. These actions are sufficient to attract the attention of spectators and cause them to read the advertisement.

While but one form of the invention is shown in the drawings, it is not desired to limit this 25 application for patent to the particular construction indicated, otherwise than limited by the prior art, as it is appreciated that other forms might be made that would use the same principles and come within the scope of the appended 30 claims.

Having thus described the invention, what is claimed is:—

1. A signboard for trailers comprising in combination, a housing with a plurality of walls, 35 signs within the walls made of pivoted slats with sign wording on both sides, means for rotating the slats, mechanism for connecting said means together to operate uniformly with one another, and manual control for operating the slats independently. 40

2. A signboard of the class described comprising in combination, a rectangular housing having openings in four walls and the top, a plurality of signs mounted in the housing and appearing in the openings, said signs consisting of moveable slats adaptable to be variably positioned in the openings to provide different sign wording thereon, means for operating the slats intermittently, and means for operating the last 50 mentioned means. 45

3. A signboard of the class described comprising in combination, a rectangular housing having openings in four walls and the top, a plurality of signs mounted in the housing and appearing in the openings, said signs consisting of moveable slats adaptable to be variably positioned in the openings to provide different sign wording thereon, means for operating the slats intermittently, means for operating the last 60 mentioned means, and illumination means for varying the lighted appearance of the signs mounted exteriorly to the signs, and windows for protecting the signs. 55

EDWARD S. CORCORAN. 65
